UNITED STATES PATENT OFFICE.

EUGÉNE RIBEYRE, OF LYON, FRANCE.

SUPPORT FOR PLAYING-CARDS FOR USE BY CARD-PLAYERS.

1,286,780.

Specification of Letters Patent.

Patented Dec. 3, 1918.

Application filed June 28, 1917. Serial No. 177,563.

To all whom it may concern:

Be it known that I, EUGÉNE RIBEYRE, of Lyon, France, a citizen of the French Republic, have invented a certain new or Improved Support for Playing-Cards for Use by Card-Players, of which the following is a specification.

The support for playing cards intended for use by card-players which forms the subject of the invention is characterized by the general arrangement of its construction. The device is intended to obviate the necessity of holding the cards in the hand the cards being arranged in a holder mounted on the support in such manner that the cards can be easily read, owing to the variable inclination which can in certain cases be given to the support.

The present device is intended particularly for the use of persons crippled or paralyzed in one arm or a hand as it enables them to arrange their cards without difficulty in the desired position and to play with the only available hand.

25 The annexed drawings illustrate the invention.

Figure 1 is a front view of the card-holding support part being in section.

Fig. 2 is a side view thereof, part being shown in section on line B—B of Fig. 1.

Referring to the drawings the support 17 is fixed to the edge of a table 18 by means of the clamp 20 and its screw 21 it can be turned around the axis 22 and can be maintained in the position selected by tightening the milled button 23.

The cards can be inclined as desired, and if required completely turned down by the following means.

40 The support 17 is jointed by the swivel 24 to the socket 25 of the card holder, which, by its fan-shaped arrangement and concave form reproduces exactly the ordinary position of cards held in the human hand. A milled button 26 enables the holder to be fixed at the inclination preferred by the player.

50 The holder into which the cards are inserted is composed essentially of the three following parts: a semi-circular back plate 27 forming a curved back support for the cards; a front plate 28 of similar shape but of lesser diameter, and a spindle 29 for con-

necting by means of a screw-threaded milled button 30 the two plates 27 and 28. The 55 cards 31 are arranged and fixed between the two plates. The cards are engaged by their edges against the edge of a semi-circular felt strip 32 fastened to the front of the plate 27 and are retained between the two 60 plates by means of a strip 33 of elastic material, such as: cloth, felt rubber, etc., fixed to the inside of the front plate 28.

A pin 34 fixed to the plate 27 and engaging in a corresponding hole in the plate 28 65 allows of maintaining the position between the two plates. By loosening or tightening the button 30 the pressure exerted on the cards by the strip 33 can be regulated according to the number of cards displayed 70 or left in the holder.

The cards can be turned down from the position shown in Fig. 2 to that represented in dotted lines by simply pressing down the 75 holder.

What I claim as my invention and desire to secure by Letters Patent of the United States is:—

1. A support for playing cards for the use of persons deprived of the use of one hand, comprising a gripping device for the cards, means for regulating the pressure of said device upon the cards, an arm attached to said gripping device, a support to which said arm is hinged so that the gripping device and the cards can be inclined or completely turned downward, a milled button for fixing the gripping device in the desired inclined position, a clamp for fixing said support to a table, means connecting said support to said clamp, whereby the holder and gripping device can be turned around a vertical axis, and means for fixing the holder in the latter adjusted position. 80 85 90

2. A support for playing cards comprising a semi-circular plate, an abutment thereon, a second semi-circular plate, an elastic strip thereon, means for pressing said plates together, means for regulating the pressure of said device upon the cards, an arm attached to card gripping device, a support to which said arm is hinged so that the gripping device and the cards can be inclined or completely turned downward, a milled button for fixing the gripping device 100 105 in the desired inclined position, a clamp for

fixing said support to a table, a vertical pivot upon the upper surface of said clamp, a horizontal plate fixed to the lower end of said support and rotatable about said pivot whereby said support can be turned upon said pivot, and a milled button for fixing said support in the adjusted position.

In witness whereof I have signed this specification in the presence of two witnesses.

EUGÉNE RIBEYRE.
